UNITED STATES PATENT OFFICE.

JOSEPH E. BIRMINGHAM AND CHARLES GRANDJEAN, OF SAN FRANCISCO,
CALIFORNIA.

DESIGN FOR A SPOON.

SPECIFICATION forming part of Design No. 22,223, dated February 14, 1893.

Application filed December 19, 1892. Serial No. 455,701. Term of patent 3½ years.

To all whom it may concern:

Be it known that we, JOSEPH E. BIRMINGHAM and CHARLES GRANDJEAN, citizens of the United States, residing in the city and county of San Francisco, State of California, have invented and produced a new and original Design for Spoons, of which the following is a specification, reference being had to the accompanying drawing, showing a part thereof.

10 The leading feature of our design consists in the bowl of the spoon having the figure of a ship delineated therein, and the handle with the figure of a man standing upon a globe holding a staff with a banner in one hand, and

15 a sword in the other.

A is the bowl of a spoon, having engraved or otherwise delineated in the concaved portion of the bowl, the figure of a ship of the fifteenth century. The handle of the spoon

20 is gradually increased in diameter from the

shank just above the bowl, and the upper end has an irregular ornamental outline B. Within this end of the spoon is delineated the figure C of a man in the dress of the fifteenth century, and standing upon the figure D of a globe. 25 The figure of the man is intended to represent Columbus holding a sword in the right hand, and a staff with a banner upon it in the left. Below the globe are scrolls and between these scrolls a vine or branch with leaves upon it 30 is delineated.

What we claim is--

The design for a spoon as herein shown and described.

JOSEPH E. BIRMINGHAM.
CHARLES GRANDJEAN.
